By Howard E. Barlow ATTORNEY.

UNITED STATES PATENT OFFICE.

THEODORE W. FOSTER, OF PROVIDENCE, RHODE ISLAND, ASSIGNOR TO THEODORE W. FOSTER & BRO. CO., OF PROVIDENCE, RHODE ISLAND, A CORPORATION OF MAINE.

FASTENER.

Application filed December 20, 1921. Serial No. 523,733.

To all whom it may concern:

Be it known that I, THEODORE W. FOSTER, a citizen of the United States, residing at Providence, in the county of Providence and State of Rhode Island, have invented certain new and useful Improvements in Fasteners, of which the following is a specification.

- This invention relates to flexible, extensible bracelets more particularly of that class which is provided with pendants, one of the pendant connectors being adapted to slide through an eyelet or loop on the opposite end of the bracelet, to permit the separating of the bracelet ends to permit the bracelet to be readily passed over the hand of the wearer, and the object of this invention is to provide simple and effective means whereby the ends of such a bracelet may be releasably connected together when in operative position to prevent the ends from separating and the bracelet from becoming lost by being thrown or dropped from the wrist of the wearer.
- With these and other objects in view, the invention consists of certain novel features of construction, as will be more fully described, and particularly pointed out in the appended claims.

30 In the accompanying drawings:

Figure 1 is a perspective view illustrating the ends of a bracelet as being releasably locked or retained in closed position.

- Figure 2 illustrates the end portions of a bracelet as being released from the locking device permitting them to be freely moved to open position by drawing the flexible connector which is attached to one end of the bracelet through the eye or loop on the opposite end thereof.

- It is found in practice that where a flexible bracelet is used having its ends joined simply by a pendant member through a flexible connector, that such a connector is too readily drawn through its eye or loop permitting the ends to separate and the bracelet to be lost from the wrist; to obviate this objection I have provided a simple and effective means whereby these bracelet ends may be releasably locked or connected together so that their ends cannot be accidentally separated thereby effectually preventing the bracelet from being lost, and the following is a detailed description of one

means by which this locking effect may be accomplished:

With reference to the drawings, 10 designates the body portion of a bracelet, which is usually formed of flexible material such as woven wire, chain, ribbon band or the like, to the ends of which are connected caps or end pieces 11. In each of these pieces I have connected a loop or eye 12 and 13. In the eye 12 I have connected an elongated resilient loop member 14, preferably formed of wire, bent to provide a retaining shoulder 15, the opposite end 16 of the loop being left free to permit the ring or eye 17 to be forced or sprung thereover.

In this loop 14 I have connected one end 70 of a chain 18 which extends through the ring or eye 17 on the opposite end of the bracelet, the opposite end of the connector being attached to a pendant 19 whereby when it is desired to draw the ends of the 75 bracelet together it is only necessary to pull the pendant 19 through the ring or eye 17 and to contract this loop by forcing this ring or eye over the shoulder 15 of this loop whereby the ends of the bracelet are detachably locked together to prevent them from accidentally separating and so prevent loss of the bracelet, which when enlarged by the slipping of the connector through the ring or eye 17, is liable to be thrown or dropped 80 from the wrist of the wearer.

In order to render the bracelet more attractive in appearance I have attached another pendant 20 to the ring or eye 17, which hangs with the pendant 19 when the 85 ends of the bracelet are in closed position as illustrated in Figure 1, also to render the bracelet still more ornamental I have shown an ornamental saddle member 21 which is adjustably mounted on the body 95 of the bracelet.

My improved locking device for the ends of a flexible bracelet is extremely simple and practical in construction and effective in its operation and by its use the ends of a bracelet may be securely locked together and prevented from separating when under tension or strain.

The foregoing description is directed solely towards the construction illustrated, but I desire it to be understood that I reserve the privilege of resorting to all the mechanical changes to which the device is

susceptible, the invention being defined and limited only by the terms of the appended claims.

I claim:

- 3 1. A fastener comprising an eye member, a fastener member adapted to engage said eye, a flexible member passed through said eye and connected with said fastener, and a stop on said flexible member limiting 10 movement thereof in one direction through said eye.
- 15 2. A fastener comprising an eye member, means for securing said eye to an element, a fastener member adapted to engage said eye, means for securing said eye to an element, and a chain carried by the fastener and extending through said eye and having an enlargement on its outer end to engage the eye and limit the movement thereof in 20 one direction.
- 25 3. A fastener including an eye member, a fastener member for engaging said eye comprising a resilient loop having a shoulder thereon to releasably retain said fastener in said eye, and a flexible member carried by said loop and passed through said

eye and having an enlargement on its outer end to limit the separating movement of said fastener members.

4. A fastener comprising an eye member, 30 a wire loop pointed at one end and provided with oppositely extending yielding shoulders for engaging and releasably retaining said fastener in the eye, and a flexible member carried by the fastener and 35 passed through the eye and having a stop member on its outer portion to engage the eye and limit the separating opening movement of said members.

5. A fastener comprising a ring member 40 having an attaching socket yieldably connected thereto, a yieldable fastener for engaging the ring and having an attaching socket member yieldably connected thereto, and a flexible connector attached at one 45 end to said fastener and slidably extending through said ring and having an enlargement at its other end to engage the eye and limit the separating movement of said fastener members.

In testimony whereof I affix my signature.
THEODORE W. FOSTER.
